UNITED STATES PATENT OFFICE.

HARRIS L. ROSENTHAL, OF NEW YORK, N. Y.

CHALK-SHARPENER.

1,332,068.

Specification of Letters Patent. Patented Feb. 24, 1920.

Application filed September 20, 1919. Serial No. 325,176.

To all whom it may concern:

Be it known that I, HARRIS L. ROSENTHAL, a citizen of the United States, and a resident of the city of New York, borough of Manhattan, in the county of New York and State of New York, have invented a new and Improved Chalk-Sharpener, of which the following is a full, clear, and exact description.

This invention relates to improvements in chalk sharpeners, an object of the invention being to provide a device of the character stated, which will perfectly sharpen the chalk and perform the function quickly and economically.

Heretofore, chalk, such as is used by the needle industry and the like, has usually been sharpened or scraped by means of an ordinary knife. This not only consumes considerable time but results in an imperfectly sharpened article and is also extremely unsatisfactory as the fine particles of chalk are scattered about and wasted. With my improved device the fine particles of chalk or wax are deposited in a receptacle, and the chalk cutter kept clean by means of the particles falling therethrough. The entire operation is a time and labor saving one and also results in a better marking device and in an economy of chalk.

A further object is to provide a device of the character stated which permits a convenient assemblage of marking devices, erasing devices, heating means and sharpening means so as to save time in locating these several adjuncts of the tailoring or other trade.

With these and other objects in view the invention consists in certain novel features of construction, and combinations and arrangements of parts, as will be more fully hereinafter described and pointed out in the claims.

In the accompanying drawings—

Figure 1 is a view in front elevation partly broken away illustrating my improvements;

Fig. 2 is a view in transverse section on the line 2—2 of Fig. 1;

Fig. 3 is a top plan view;

Fig. 4 is a fragmentary end view; and

Fig. 5 is a view in section on the line 5—5 of Fig. 3.

1 represents a casing which is of general rectangular form open at its front and top and having a horizontal partition 2 therein providing a space for a box of chalk 3 be-

low the partition and supporting an empty box 4 above the partition to catch the particles of chalk. A piece of chalk is indicated by the reference numeral 12 and while this article is commonly known in the trade as chalk, it is composed largely or entirely of wax and hence I use the trade name to indicate an article which is used for marking on cloth and commonly known as chalk. 65

Wire bails 5 and 6 are connected to the ends of the casing and adapted to hang in front of the casing to hold the boxes 3 and 4 against possibility of accidental displacement. A serrated cutter or scraper 7 is located in the upper portion of the casing and has its ends secured to the back 8 of the casing and on this cutter or scraper the chalk is adapted to be moved to sharpen the same. A supporting bar 9 angular in cross-section is secured to the ends of the casing and is located adjacent to and in alinement with the upper edge of the cutter, and a guard plate 10 is positioned at an incline and at its upper forward edge projects over the cutter 7. This guard 10 prevents contact of the fingers with the cutter during the sharpening operation and also acts as a deflector to direct downwardly flying particles of chalk. 85

The cutter 7 is of relatively thin metal so that when it is corrugated and located edgewise as shown, its upper edge presents a cutting or scraping surface which effectually removes the material of the chalk when the latter is reciprocated longitudinally of the cutter as a whole. The chalk is held in the position shown in dotted lines in Fig. 2 and moved along the edge of the cutter so as to scrape the chalk and give it a sharp edge. 90

The cutter 7, by reason of the fact that it is of thin metal, provides a cutting edge 7^a throughout its upper surface.

The guard plate 10 is spaced from a flange 11 on the back 8 and provides a space in which the chalk indicated at 12 may be deposited ready for convenient use. A coiled spring 13 is secured to one end of the casing and is adapted to support pencils 14. A 105 similar coiled spring 15 is secured to the back of the casing and is adapted to support a chalk eraser 16. This eraser has a curved smooth end 17 which is adapted, when heated, to be moved over a chalk mark on the 110 goods and by reason of the heat will remove the chalk mark.

To heat the iron I provide a device, such as shown most clearly in Fig. 5, which consists of a cup 18 fixed to the back of the casing and adapted to receive the small particles of wax which are scraped or cut from the chalk. These particles of wax, indicated by the reference numeral 19, are deposited in the cup 18 and a wick 20 of any approved form is positioned in the wax and when this wick is lighted, it serves as a heater for the eraser 16.

It will thus be noted that with my improved device the chalk marking devices, such as pencils, and an eraser are conveniently located so that the device not only operates as a chalk sharpener, but is a time saver as well.

Various slight changes may be made in the general form and arrangement of parts described without departing from the invention, and hence I do not limit myself to the precise details set forth but consider myself at liberty to make such changes and alterations as fairly fall within the spirit and scope of the appended claims.

I claim:

1. A chalk sharpener, comprising a casing, a cutter secured at its ends to a wall of the casing and at its intermediate portion being spaced from said wall and serrated longitudinally, and a supporting bar located in front of the cutting edge of the cutter and in horizontal alinement therewith.

2. A chalk sharpener, comprising a casing, a cutter secured at its ends to a wall of

the casing and at its intermediate portion spaced from said wall and serrated longitudinally, a supporting bar located in front of the cutting edge of the cutter and in horizontal alinement therewith, and an inclined 40 guard plate having its upper edge projecting over the inner edge of said cutter.

3. A chalk sharpener, comprising a casing, a partition in the casing adapted to receive a box of chalk below the partition, 45 and an empty box on the partition, hinged bails connected to the ends of the casing and adapted to project over the front of the casing to confine the boxes, and a cutter located above the empty box support.

4. A chalk sharpener, comprising a casing, a stationary cutter in the upper portion of the casing, a horizontal partition in the casing below the cutter, said partition and the bottom of the casing adapted to support 55 boxes, and bails pivotally connected at their ends to the ends of the casing and at their intermediate portions normally located in front of the boxes on the partition and the bottom of the casing.

5. A chalk sharpener, comprising a casing, a stationary cutter in the casing, supports on the outside of the casing adapted to receive pencils and a chalk eraser therein, a receptacle on the casing adapted to receive the particles of chalk from the cutter, and a wick located in said particles of chalk and constituting a heater for the chalk eraser.

HARRIS L. ROSENTHAL.
